(57) **CLAIM**

The ornamental design for a pumping bra, as shown and described.

DESCRIPTION

FIG. 1 is a top view of embodiment one of a pumping bra showing my new design;

FIG. 2 is a front elevation view thereof;

FIG. 3 is a right side view thereof, the left side view being a mirror image thereof;

FIG. 4 is a bottom view thereof;

FIG. 5 is a rear elevation view thereof;

FIG. 6 is a front perspective view thereof in a wrapped around configuration;

FIG. 7 is a front perspective view thereof in a wrapped around configuration with a cutaway section on the left side exposing the end of the material behind the outer layer and then a stretched position on the right side exposing the opening that can be created between the two layers;

FIG. 8 is a top view of embodiment two of a pumping bra showing my new design;

FIG. 9 is a front elevation view thereof;

FIG. 10 is a right side view thereof, the left side view being a mirror image thereof;

FIG. 11 is a bottom view thereof;

FIG. 12 is a rear elevation view thereof;

FIG. 13 is a front perspective view thereof in a wrapped around configuration; and,

FIG. 14 is a front perspective view thereof in a wrapped around configuration with a cutaway section on the left side exposing the end of the material behind the outer layer and then a stretched position on the right side exposing the opening that can be created between the two layers.

The dot dash broken line indicates cutaway boundaries that form no part of the claim. The evenly dashed lines represent stitching that form no part of the claimed design.
